RAILWAY SIGNALING

James J. Vanhorn, Swissvale, Pa., assignor to
The Union Switch & Signal Company, Swiss-
vale, Pa., a corporation of Pennsylvania

Application February 15, 1936, Serial No. 64,095

14 Claims. (Cl. 246—50)

My invention relates to railway signaling, and particularly to signaling involving wayside signals located along a trackway for governing the passage of trains.

5 A feature of my invention is the provision of novel and improved apparatus for establishing a distinctive control for each of three track sections in the rear of an occupied section. Each distinctive control is effective to cause a corresponding aspect of the wayside signals, whereby there is produced a three-block, four-indication, system of signaling.

10 I will describe two forms of apparatus each embodying my invention, and will then point out 15 the novel features thereof in claims.

In the accompanying drawings, Figs. 1A and 1B are diagrammatic views which, when placed end to end in the order named, illustrate one form of apparatus embodying my invention. Fig. 2 is 20 a diagrammatic view illustrating a modification of the apparatus shown in Fig. 1A and also embodying my invention.

Similar reference characters refer to similar parts in each of the several views.

25 Referring first to Figs. 1A and 1B, the reference characters 5 and 6 designate the rails of a stretch of railway track over which traffic normally moves in the direction indicated by the arrows. These rails are divided by insulated joints 30 7 into a plurality of track sections designated by the reference character T with a suitable distinguishing prefix 1, 2, 3, 4, etc.

Each track section is provided with a track circuit which includes a track battery 8 connected 35 across the rails at one end of the section and a track relay, designated by the reference character TR with a prefix the same as the prefix in the reference character of the associated section, connected across the rails at the other end of the 40 section.

To govern the passage of trains through the stretch of railway, a wayside signal, designated by the reference character the same as the prefix in the reference character of the associated section, is located at the entrance of each track section. Each of these signals comprises an upper 45 unit U and a lower unit L. These signals may take any one of several forms of signal mechanism such as the semaphore, color light, search-

50 light, or position light. As here illustrated, each upper unit U is a searchlight signal such as described and claimed in the United States Letters Patent No. 1,864,224, granted June 21, 1932, to W. B. Wells, for Light signals. For the purpose 55 of this application, it is deemed sufficient to but

briefly describe these signals. Referring to signal 1, for example, the upper unit U includes a pivotally mounted rotor 12 controlled by a permanent magnet (not shown) and by an operating winding 13. Energization of the operating winding 13 with current of one polarity causes the rotor 12 to be rotated in one direction moving the signal to the clear indication position; energization of the operating winding 13 with current of reverse polarity causes the rotor 12 to be rotated in the opposite direction to move the signal to the caution indication position; while deenergization of the operating winding 13 permits the rotor 12 to be returned by gravity to a center position which is the stop indication position. Associated with rotor 12 is a lamp 1UE which may be lighted constantly as shown or which may be approach lighted in any well-known manner. As pointed out in detail in the aforementioned patent, when the rotor 12 is rotated to the clear position, a green colored filter G is moved in front of the lamp 1UE so that a green signal light is displayed. When the rotor 12 is rotated to the caution indication position, a yellow colored filter Y is moved in front of the lamp 1UE so that a yellow signal light is 25 displayed. In like manner, the positioning of the rotor 12 in the center position moves a red colored filter R in front of the lamp 1UE so that a red signal light is displayed. The rotor 12 actuates a set of circuit controlling contacts in 30 such a manner that the contact 14—15 is closed only in the clear indication position, the contact 16—17 is closed only in the caution indication position, and the contact 14—18 is closed both in the stop and caution indication positions.

35 The lower unit L of the signal 1 likewise comprises a rotor 20, an operating winding 21, and a lamp 1LE, all of which operate in a manner similar to that described for rotor 12, operating winding 13, and lamp 1UE of the upper mechanism except that the lower unit is arranged to display a red signal light and a green signal light but not a yellow light and each lower unit L is provided with a contact 22—23 which is closed in the clear indication position.

45 Each of the wayside signals comprises an upper and a lower unit each of which functions in a manner similar to that described for the upper and lower units of signal 1.

Associated with each signal is a polarized signal 50 control relay designated by the reference character D with a prefix the same as the reference character of the signal controlled by that relay. Each signal control relay D is controlled over a two-wire polarized line circuit which is governed 55

by the track relay for the section with which such signal control relay is associated as well as by the signal control relay, the track relay, and the signal contacts associated with the section 5 next in advance.

Each of the searchlight signals herein shown is controlled by the associated track relay TR and the associated signal control relay D in the following manner: When both relays are deenergized (see signal 4), energy is disconnected from both upper and lower units so that signal 4 displays a red light over a red light to indicate "stop". When track relay TR is energized and relay D is deenergized (see signal 3), operating 10 winding 13 of the upper unit U of that signal is energized in the reverse direction by a circuit which passes from terminal B of a suitable source of energy through front contact 25 of relay 3TR, back point of contact 26 of relay 3D, winding 13, 15 back point of contact 27 of relay 3D, and front contact 28 of relay 3TR to terminal C of the same source of current. Signal 3, therefore, displays a yellow light over a red light to indicate "approach next signal prepared to stop". When 20 track relay TR is energized and relay D is energized in the reverse direction (see signal 2), operating winding 13 of the upper unit U of that signal is energized in the reverse direction by a circuit which passes from terminal B through 25 front contact 30 of relay 2TR, front point of contact 31 of relay 2D, reverse polar contact 32-33 of relay 2D, winding 13, reverse polar contact 34-35 of relay 2D, front point of contact 36 of relay 2D, and front contact 37 of relay 2TR to 30 terminal C, and operating winding 21 of the lower unit L of that signal is energized in the normal direction by a circuit which passes from terminal B through front contact 30 of relay 2TR, caution and stop signal contact 38-39 of the upper unit, 35 caution signal contact 40-41 of the upper unit, front contact 42 of relay 2D, reverse polar contact 43-44 of relay 2D, winding 21, reverse polar contact 45-46 of relay 2D, front contact 47 of relay 2D, and front contact 37 of relay 2TR to 40 terminal C. Signal 2, therefore, displays a yellow light above a green light to indicate "approach next signal at medium speed". When relay TR is energized and relay D is energized in the normal direction (see signal 1), operating winding 13 of the upper unit U of that signal is 45 energized in the normal direction by a circuit which passes from terminal B through front contact 48 of relay 1TR, front point of contact 49 of relay 1D, normal polar contact 52-50 of relay 50 1D, winding 13, normal polar contact 51-35 of relay 55 1D, front point of contact 52 of relay 1D, and front contact 53 of relay 1TR to terminal C. Signal 1, therefore, displays a green light above a red light to indicate "proceed at normal speed".

As shown in the drawings, the section 4T is 60 occupied by a train K so that both relays 4TR and 4D are deenergized with the result that signal 4 indicates "stop". When relay 4TR is deenergized, no current is supplied to the line circuit for relay 3D with the result that relay 3D is deenergized and relay 3TR is energized. When relay 3TR is energized and relay 3D is deenergized, relay 2D becomes energized in the reverse direction over a line circuit which passes from terminal B, at signal 3, through front contact 25 of relay 3TR, caution and stop signal contact 55-56 of the upper unit, caution signal contact 57-58 of the upper unit, back point of contact 59 of relay 3D, front contact 60 of relay 2TR, relay 70 2D, front contact 61 of relay 2TR, back point of

contact 62 of relay 2D, and front contact 28 of relay 3TR. When relay 2TR is energized and relay 2D is energized in the reverse direction, relay 1D is energized in the normal direction over a line circuit which passes from terminal B, at signal 2, through front contact 30 of relay 2TR, upper mechanism stop and caution contact 38-39, upper mechanism caution contact 40-41, lower mechanism clear contact 64-65, front point of contact 66 of relay 2D, front contact 67 of relay 1TR, relay 1D, front contact 68 of relay 1TR, front point of contact 69 of relay 2D, and front contact 37 of relay 2TR to terminal C. When relay 1TR is energized and relay 1D is energized in the normal direction, the line circuit for the signal next in rear (not shown) is supplied with current of normal polarity over a circuit which includes front contacts 48 and 53 of relay 1TR, front points of contacts 70 and 72 of relay 1D, and clear contact 14-15 of the upper unit of 20 signal 1.

It will be noted that the two less restrictive proceed indications cannot be displayed if the signal mechanism in advance is occupying its stop condition. For example, the line circuit for signal 2 is supplied with energy over both the stop and caution contacts 55-56 of the upper unit and the caution contact 57-58 of the upper unit, and the line circuit for signal 1 is supplied with energy over the stop and caution contact 38-39 of the upper unit, and the caution contact 40-41 of the upper unit as well as the clear contact 64-65 of the lower unit. In a similar manner, the line circuit for the signal (not shown) next in rear of signal 1 is supplied with energy over the clear contact 14-15 of the upper unit. The system embodying my invention, therefore, provides against the possibility of a train receiving either of the two less restrictive indications when the signal next in advance is displaying the stop indication even though the controlling relays might be in such condition as would provide for such less restrictive indications.

It will also be noted that the polarized relays D are of the retained neutral type. That is, these relays are arranged so that their neutral armatures do not release when the polarity of the line circuit is being charged. This characteristic prevents tumble-down of the signals to the rear when the line circuit is being pole changed since, during these periods, the front neutral contacts of the relays D remain closed so that energization of the line circuit to rear is not disturbed.

Furthermore, it will be noted that the polarized relays have a slow pickup characteristic which prevents a momentary flash of the wrong indication when the signal next in advance is passed by a short engine or car traveling at high speed. For example, if a light engine should pass signal 2 at such speed as to permit track relay 1TR to become energized before track relay 2TR becomes deenergized, the line circuit for the control of signal 1 would be supplied momentarily with current of normal polarity. Relay 1D, however, having a slow pickup characteristic, remains in its released condition until track relay 2TR becomes deenergized to disconnect energy from the line circuit for relay 1D. Signal 1, therefore, changes from its red over red indication to its yellow over red indication without flashing a momentary less restrictive indication.

Referring next to Fig. 2, the apparatus shown herein is similar to the apparatus illustrated in Fig. 1A except that the control for the lower 75

unit L at each signal has been modified to provide a green light over a green light instead of a green light over a red light for the proceed at normal speed indication.

5 It will be noted that the operating winding 21 of each lower unit L is energized in the normal direction when both the associated relays TR and D are energized regardless of the direction of energization of the relay D. That is, the 10 lower units L of both signals 1 and 2 are energized over identical circuits so that the lower unit L of each signal displays a green signal light. The circuit at signal 2 passes from terminal B through front contact 74 of relay 2TR, front contact 15 15 of relay 2D, winding 21, front contact 76 of relay 2D, and front contact 77 of relay 2TR to terminal C.

It will be noted also that the line circuit for two less restrictive indications cannot be energized if the signal in advance is in its "stop" condition. For example, when relay D is energized, the line circuit for the signal next in rear is energized over one circuit (see signal 1) which includes the clear contact 78-79 of the 25 upper unit and the clear contact 80-81 of the lower unit, or over another circuit (see signal 2) which includes the stop and caution contact 82-83 of the upper unit and the caution contact 84-85 of the upper unit as well as the clear 30 contact 86-87 of the lower unit. When the relay D is deenergized, the line circuit for the signal next in rear is supplied with energy over a circuit which includes stop and caution contact 82-83 and caution contact 84-85. Otherwise, 35 the modification shown in Fig. 2 operates in a manner similar to that described for the system shown in Figs. 1A and 1B.

It is understood that although signals 1 and 2 only are shown in Fig. 2, each of the remaining 40 signals of my system also may be controlled in a similar manner.

From the foregoing description of the two forms of apparatus each embodying my invention, it will be apparent that I have provided a 45 simple and reliable three-block, four-indication, signal system utilizing searchlight signals wherein only two line control wires are required and wherein only one line relay and one track relay are required for each signal. Furthermore, the 50 system embodying my invention is free from tumble-down of the signals to the rear and is free from momentary flashing of misleading indications when a light engine traveling at high speed passes from one section to another.

55 Although I have herein shown and described only two forms of apparatus embodying my invention, it is understood that various changes and modifications may be made therein within the scope of the appended claims without departing from the spirit and scope of my invention.

Having thus described my invention, what I claim is:

1. A railway signal system comprising, a plurality of successive sections of railway track, each such section having a track circuit including a track relay, a signal for each section, each such signal having a mechanism responsive to the polarity of the current supplied thereto, a line circuit for each section governed by the associated track relay, a polarized line relay for each section connected to the line circuit for that section, contacts of each line relay for reversibly governing the line circuit for the section next in rear of the associated section and for reversibly

governing the mechanism of the associated signal, and means including front contacts of each track relay for supplying current to said contacts of the associated line relay if and only if such track relay is energized. 5

2. A railway signal system comprising, a plurality of successive sections of railway track, each such section having a track circuit including a track relay, a signal for each section having contacts operably governed by the condition of the 10 signal, a line circuit for each section controlled by the associated track relay, a polarized line relay for each section for governing the associated signal and connected to the line circuit of that section, contacts of each line relay for reversibly governing the line circuit for the section next in rear of the associated section, and means at each signal including the contacts operably governed by that signal for supplying current to 15 said contacts of the associated line relay. 20

3. In combination, a section of railway track having a track circuit including a track relay, a signal for said section and having two mechanisms each selectively responsive to the polarity of the current supplied thereto whereby said signal is capable of displaying a stop aspect and at least three different proceed indications having varying degrees of speed restriction, a line circuit reversibly governed by traffic conditions in advance of said section and including a contact 25 of said track relay, a polarized line relay connected to said line circuit, circuit means including only neutral contacts of both said relays for establishing one of said proceed indications, and circuit means including neutral contacts of both 30 said relays and polar contacts of said line relay for establishing the other two proceed indications. 35

4. A railway signal system comprising, a stretch of railway track divided into sections, a 40 neutral relay and a polarized relay for each section, a track circuit for governing each said neutral relay, a line circuit for governing each said polarized relay, means controlled jointly by said two relays for selectively supplying current of 45 normal polarity or reverse polarity or supplying no current to the line circuit for the section next in rear, and a signal for each section responsive to the polarity of the current supplied thereto and controlled by the two relays of that section 50 in such manner that a first aspect is displayed when the neutral relay is deenergized, a second aspect is displayed when the neutral relay is energized and the polarized relay is deenergized, a third aspect is displayed when the neutral relay is energized and the polarized relay is energized reverse, and a fourth aspect is displayed 55 when the neutral relay is energized and the polarized relay is energized normal.

5. A railway signal system comprising, a 60 stretch of railway track divided into sections, a neutral relay and a polarized relay for each section, a track circuit for governing each said neutral relay, a line circuit for governing each said polarized relay, means controlled jointly by 65 said two relays for selectively supplying current of normal polarity or reverse polarity or supplying no current to the line circuit for the section next in rear, and a signal for each section responsive to the polarity of the current supplied thereto and controlled by both relays for that section in such manner that a stop indication is displayed when the neutral relay is deenergized and three different proceed indications are displayed when the neutral relay is energized ac- 70 75

cording as the polarized relay is deenergized or energized reverse or energized normal respectively.

16. In combination, two sections of railway track, each having a track circuit including a track relay, a signal for the forward section governed by the track relay for that section and comprising a first unit and a second unit each capable of displaying different indications in response to the polarity of the current supplied thereto, contacts operably governed by said two units, a line circuit for the rear section governed by said contacts, a line relay connected to said line circuit, and a signal for the rear section governed by said line relay and by the track relay for that section.

7. In combination, two sections of railway track, a signal for the forward section governed by traffic conditions in advance of the signal and comprising a first mechanism and a second mechanism, said first mechanism operable to three different conditions according as it is energized normal or energized reverse or deenergized respectively and said second mechanism operable to two different conditions according as it is energized or deenergized respectively, contacts operably connected to each mechanism and each closed only when the associated mechanism is energized, a signal for the rear section, and circuit means including said contacts for governing said signal for the rear section.

8. In combination, two sections of railway track, a signal for the forward section governed by traffic conditions in advance of the signal and comprising two units, one unit capable of displaying three different indications according as it is energized normal or energized reverse or deenergized and the other unit capable of displaying two different indications according as it is energized or deenergized, contacts governed in accordance with the indications displayed by said two units, a relay for the rear section governed by said contacts, and a signal governed by said relay.

45. 9. In combination, two sections of railway track, a signal for the forward section governed by traffic conditions in advance of said signal and comprising one indication unit capable of displaying a proceed or a caution or a stop indication according as it is energized normal or energized reverse or deenergized respectively and another indication unit capable of displaying a proceed or a stop indication according as it is energized or deenergized respectively, a first contact closed only when said one unit is energized normal, a second contact closed only when said one unit is energized reverse, a third contact closed only when said other unit is energized, a relay for the rear section, a circuit for said relay including said first contact, another circuit for said relay including said second and said third contact, still another circuit for said relay including said second contact, and a signal for the rear section controlled by said relay.

65. 10. In combination, a section of railway track including a track circuit having a source of energy connected across the rails at one end of the section and a track relay connected across the rails at the other end of the section, a polarized line relay for said section, said line relay supplied with current of normal polarity or with current of reverse polarity or with no current in accordance with traffic conditions in advance of said section, a signal for said section comprising a first unit and a second unit, a circuit for the

first unit including only front contacts of said track relay and only back neutral contacts of said line relay, another circuit for said first unit including a front contact of said track relay and a front neutral contact of said line relay as well as a reverse polar contact of said line relay, still another circuit for said first unit including a front contact of said track relay and a front neutral contact of said line relay as well as a normal polar contact of said line relay, and a circuit for the second unit including a front contact of the track relay and a front neutral contact of the line relay as well as a reverse polar contact of said line relay.

11. In combination, a section of railway track including a track circuit having a source of energy connected across the rails at one end of the section and a track relay connected across the rails at the other end of the section, a polarized line relay for said section, said line relay supplied with current of normal polarity or with current of reverse polarity or with no current in accordance with traffic conditions in advance of said section, a signal for said section comprising a first unit and a second unit, a circuit for the first unit including only front contacts of said track relay and only back neutral contacts of said line relay, another circuit for said first unit including a front contact of said track relay and a front neutral contact of said line relay as well as a reverse polar contact of said line relay, still another circuit for said first unit including a front contact of said track relay and a front neutral contact of said line relay as well as a normal polar contact of said line relay, and a circuit for the second unit including a front contact of the track relay and a front neutral contact of the line relay.

12. In combination, a section of railway track including a track circuit having a source of energy connected across the rails at one end of the section and a track relay connected across the rails at the other end of the section, a polarized line relay for said section, said line relay supplied with current of normal polarity or with current of reverse polarity or with no current in accordance with traffic conditions in advance of said section, a signal for said section comprising a first unit and a second unit, a circuit for the first unit including a pair of front contacts of said track relay and a pair of back contacts of said line relay, another circuit for the first unit including said pair of front contacts of the track relay and a pair of front contacts of the line relay as well as a pair of reverse polar contacts of the line relay, still another circuit for said first unit including said pair of front contacts of the track relay and said pair of front contacts of the line relay as well as a pair of normal polar contacts of the line relay, and a circuit for the second unit including said pair of front contacts of the track relay and a pair of front contacts of the line relay.

13. In combination, a section of railway track having a source of energy connected across the rails at one end of the section and a track relay connected across the rails at the other end of the section, a line circuit for said section including a front contact of said track relay, a polarized line relay connected to said line circuit, means governed by traffic conditions in advance of said section for supplying said line circuit with current of normal polarity or with current of reverse polarity or no current, and a signal for said section controlled by said track and line relays and arranged to display a red light over a red light.

when the track relay is deenergized regardless of the condition of said line relay and a yellow light over a red light or a yellow light over a green light or a green light over a red light when said track relay is energized according as said line relay is deenergized or is energized reverse or is energized normal respectively.

14. In combination, a section of railway track having a source of energy connected across the rails at one end of the section and a track relay connected across the rails at the other end of the section, a line circuit for said section including a front contact of said track relay, a polarized line relay connected to said line circuit, means gov-

erned by traffic conditions in advance of said section for supplying said line circuit with current of normal polarity or with current of reverse polarity or no current, and a signal for said section controlled by said track and line relays 5 and arranged to display a red light over a red light when the track relay is deenergized regardless of the condition of said line relay and a yellow light over a red light or a yellow light over a green light or a green light over a green light when said 10 track relay is energized according as said line relay is deenergized or is energized reverse or is energized normal respectively.

JAMES J. VANHORN.
